(57) **CLAIM**

The ornamental design for a pet hair cleaner tool, as shown and described.

DESCRIPTION

FIG. 1 is a front, right, and top perspective view of a pet hair cleaner tool, showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof;

FIG. 7 is a bottom plan view thereof; and,

FIG. 8 is an enlarged view of the delineated region 8 in FIG. 1.

The dot-dash broken lines in FIGS. 1 and 8 form no part of the claimed design and delineate portions of the claimed design that are shown on an enlarged scale in FIG. 8.
